SEWING MACHINE

Vincent G. Terry, Beverly, Mass., assignor to
 United Shoe Machinery Corporation, Paterson,
 N. J., a corporation of New Jersey

Application March 12, 1932. Serial No. 598,458

4 Claims. (Cl. 112—219)

The present invention relates to safety devices for driving and stopping mechanisms, particularly intended for use in shoe sewing machines, in which high and low speed driving mechanisms for the sewing cam shaft of the machine are provided, the high speed mechanism being in operation during the sewing of a seam, and the low speed mechanism being thrown into operation at the end of the seam, first to reduce the speed of the driving shaft of the machine, and then to drive the shaft at a low speed before bringing the machine to rest.

In making certain adjustments on a power driven sewing machine, it frequently is necessary to turn the main sewing cam shaft of the machine by hand to a position in which the parts to be adjusted may most easily be manipulated. When the sewing shaft is driven through high and low speed driving and stopping mechanisms, and particularly where a positive stopping device is employed to automatically bring the sewing shaft to rest at a definite point, the sewing shaft cannot be turned freely until certain parts of the driving and stopping mechanism are disconnected to release the sewing shaft. In the stopping mechanism hereinafter described, to which the present invention has been applied, a low speed friction clutch not under the direct control of the operator is provided which must, in order not to endanger the operator in making adjustments, be rendered inoperative. The sewing shaft of the machine is also locked against rotation by a positive stopping lever cooperating with a cam on the sewing shaft, which lever acts against projections on the cam to bring the machine to rest at a definite point in the rotation of the sewing shaft after the seam is completed. The machine is operated during sewing through a high speed clutch actuated by a foot treadle to drive the machine from a continuously rotating driving shaft, the low speed clutch and the positive stopping lever being rendered inoperative by connections to the foot treadle while the high speed clutch is actuated to drive the sewing shaft.

The object of the present invention is to provide a safety device on a high and low speed driving and stopping mechanism for a sewing machine, which may be manually shifted from a position in which the sewing machine may be operated in the ordinary way, to a safe position in which the sewing shaft of the machine may be rotated by hand but prevented from rotation under power while adjustments to the stitch-forming devices of the machine are being made.

With the above object in view, therefore, the

present invention consists of the provision in a driving and stopping mechanism having high and low speed clutches, of a manually operable safety device for preventing operation of the high speed clutch by the clutch controlling treadle while permitting control of the low speed clutch from the treadle to allow free rotation of the sewing shaft by hand. Preferably also the safety device is arranged to permit control by the treadle of the stopping lever for positively bringing the machine to rest and locking it in a definite position so that the treadle after being rendered inoperative to actuate the high speed clutch may be utilized to release the sewing shaft from the positive stopping lever. The illustrated embodiment of the invention comprises a manually shiftable block pivoted on the connections between the driving and stopping mechanism and the treadle for movement toward and away from a position in which the shiftable block may engage actuating connections for the high speed clutch. By shifting the block from the position in which it engages the high speed clutch connections, actuation of the low speed friction clutch may be prevented, and the positive stopping device may be disengaged from the stopping cam on the cam shaft by movement of the treadle to the position in which it normally actuates the high speed friction clutch. Inasmuch as the high speed clutch is not, under these conditions, actuated and the low speed clutch and the positive stop device are rendered inoperative, the main sewing cam shaft may be freely turned by hand to any desired position without danger of an accidental application of power.

The several features of the present invention will be clearly understood from an inspection of the accompanying drawings, in which Fig. 1 is a view in front elevation of a shoe sewing machine having a driving and stopping mechanism with the preferred form of the present invention applied thereto; Fig. 2 is a sectional view on an enlarged scale taken through the line 2/2 of Figure 1; and Fig. 3 is a sectional view taken along the line 3/3 of Fig. 2, showing in plan, the safety device as applied to the illustrated machine.

The machine illustrated in the drawings is an outsole shoe sewing machine, more fully illustrated and described in the U. S. Patent No. 1,625,231 granted April 19, 1927 to Laurence E. Topham, and accordingly, so much only of the machine has been illustrated in the drawings as is necessary to indicate the connection of the present invention therewith. The work support

of the machine is indicated at 2, the needle at 4, the awl at 6, and the presser foot at 8. The machine is driven from a continuously rotating power driven countershaft 10 mounted parallel to the front of the machine in bearings carried by yokes 12 secured to the machine base. The shaft 10 may be connected to a series of other machines as in a shoe repair outfit. The shaft 10, being driven from a single prime mover, would necessarily cause the inconvenience of stopping all the machines in order to safeguard any one machine by bringing the prime mover to rest. The stitch-forming devices of the machine are operated from a main sewing cam shaft 14 which, during the sewing operation, is connected to the countershaft 10 to rotate at high speed by a high speed friction clutch carried at the left hand end of the sewing shaft 14. The sewing shaft 14 is also driven by a low speed clutch rendered operative upon disconnecting the high speed and driving the shaft in a forward direction to a stopping position and with mechanism for positively stopping the shaft in a predetermined definite position.

25 The high speed clutch to drive the main shaft 14 at high speed during normal sewing operation of the machine consists of a driven clutch member and hand wheel 20 fixed to the shaft 14 and a driving clutch member 22 loosely mounted on the shaft and movable longitudinally of the shaft into and out of engagement with the driven clutch member. The driving clutch member is formed with a peripheral groove to receive a belt 24 for connecting said member with a pulley 26 secured to the power driven counter-shaft 10. The engagement of the driving member of the clutch with the driven member is controlled by a bell crank 28 pivoted on a stud 30, the upper forked end of the vertically extending arm of which embraces the hub of the driving clutch member and carries a pair of pivoted blocks 32 engaging in a groove 34 in the hub of the driving clutch member. Upon the stud 30 is also pivoted an arm 36 having a yielding connection with the horizontally extending arm of the bell crank 28. The end of the arm 36 is formed with a lateral projection to be operated by a treadle rod 38 pivotally connected at its upper end with an arm 40 pivoted on a shaft 42. The lower end of the rod is connected with a treadle 44 fulcrumed in the base of the machine. When the treadle is depressed, the high speed clutch is actuated through connections comprising the arm 36 and the bell crank 28 to drive the main sewing shaft at high speed. The treadle and treadle rod are elevated upon release of pressure against the treadle by the action of a coiled spring 46 connected between the treadle and the base of the machine and, as the treadle rod 38 rises under the influence of the spring, the arm 36 is moved to its original position, causing the driving clutch member 22 to be disengaged from the driven clutch member 20. The low speed clutch is rendered active to drive the sewing shaft at low speed by upward movement of the treadle rod 38 when it is released to cause disengagement of the high speed clutch.

50 The main sewing shaft is slowed down and driven at the speed of operation of the low speed clutch after which the low speed clutch is automatically released and the machine brought to rest. The mechanism for effecting this operation includes a low speed driving clutch member 50 loosely mounted on the shaft 14 and a driven clutch member 52 having a sleeve mounted on

the shaft 14 to rotate with the shaft and movable longitudinally of the shaft to carry the low speed driven clutch member into and out of engagement with the driving clutch member. The driving clutch member is provided with spiral gear teeth 54 meshing with the teeth of a spiral gear 56 mounted on a continuously rotating shaft 58. The shaft 58 is continuously driven by means of a belt 60 passing about a pulley 62 fixed on the shaft and about a driving pulley 64 secured to the continuously driven counter-shaft 10. The mechanism for controlling the engagement of the low speed clutch comprises a bell crank lever 66 pivoted on the frame of the machine and carrying a cam roll 68 engaging in a cam groove 70 in the sleeve of the clutch member 52. The low speed clutch operating mechanism also comprises a lock bolt carrier 72 mounted to slide longitudinally in suitable guides in the frame and carrying at its rear end a lock bolt 74 mounted to slide vertically in the lock bolt carrier and having its upper end shaped to engage a recess 76 in the laterally extending arm of the bell crank lever 66. The lock bolt carrier is acted upon by a coiled spring 78 surrounding the carrier and interposed between a shoulder on the carrier and the rear end of a sleeve 80, threaded into the frame through which sleeve the carrier slides. The lock bolt 74 is acted upon by a coiled spring 84 which normally tends to force the lock bolt upwardly in the carrier 72 to engage its upper end in the recess of the laterally extending arm 66. The position of the lock bolt in the carrier 72 is controlled through suitable connections from the treadle rod.

100 The connections for controlling the position of the lock bolt 74 of the low speed mechanism from the treadle rod comprise a three-armed lever 86 pivoted on a stud 88 and a link 90 connecting one arm of the lever with the block secured to the lower end of the bolt. Another arm of the lever 86 carries a roll 92 arranged to be engaged by the rear end of the arm 40. As soon as the treadle is depressed far enough to maintain the members of the high speed driving clutch in engagement, the lever 86 is held in position to maintain the lock bolt 74 out of engagement with the recess in the laterally extending arm of the bell crank lever 66 by the engagement of the roll 92 with the rear end of the arm 40. When the treadle is released and the treadle rod is allowed to rise, the arm 49 is disengaged from the roll 92, allowing the lock bolt 74 to move upwardly into engagement with the bell crank 66. As soon as the sewing shaft 14 has rotated sufficiently to cause the lock bolt to become aligned with the recess 76 in the bell crank 66, the lock bolt enters into the recess, thereby holding the bell crank from movement and the sleeve of the low speed driven clutch member 52 is moved longitudinally on the main shaft 14 by the cam slot 70 to engage the driven member with the driving member 50 of the clutch and is held in position to maintain the members of the clutch in engagement until the speed of the sewing shaft is reduced and the shaft rotated through a predetermined angle. The cam slot 70 in the sleeve of the driven clutch member is so shaped that at the end of this rotation, the driven clutch member will again be disengaged from the driving clutch member 50 to permit the sewing shaft to be brought to rest. Upon the disengagement of the members of the slow speed clutch, the main shaft is arrested at a prede- 110

terminated point by positively acting stopping devices.

The devices for positively stopping the rotation of the main shaft 14 at a predetermined point comprise a stopping lever 94 mounted by trunnion pins 96 on a sleeve 98 loosely surrounding a shaft 100, and a cam 102 fixed to the sewing shaft 14 and provided with a shoulder portion 104 adapted to be engaged by the upper end 10 of the stopping lever 94. The upper end of the lever 94 may be swung into and out of the path of the shoulder 104 on the cam by swinging the lever about the axis of the trunnion pins 96 and is held out of this position by a horizontally extending arm of the lever which overlies the third arm of the three arm lever 86 during the time in which the treadle is depressed. The lever 94 is swung in a direction toward the path of the cam shoulder upon elevation of the treadle and treadle rod by a coiled spring 106 connected between a horizontal arm of the lever 94 and a bracket 108 attached to the frame of the machine. The cam 102 is so located on the main shaft 14 that the shoulder 104 on the cam will strike the stopping lever 94 shortly after the low speed driven clutch member is disengaged from the driving member 50, thus positively bringing the machine to rest at a definite point.

The safety device, according to the present invention, comprises means for rendering the actuating bell-crank 28 for the high speed clutch inoperative from the treadle 44, so that the lock bolt 74 of the low speed clutch mechanism and the stopping lever 94 may be disengaged from their respective operating positions by downward movement of the treadle without causing the machine to be driven at high speed. This device consists of a block 110 pivotally mounted above the arm 36 on a stud 112 formed at one end with a clamp member 114 secured to the treadle rod 38. In the normal position of the block, shown in Fig. 2, downward movement of the treadle rod 38, when the treadle is depressed, causes the block to strike the arm 36 and actuate the high speed clutch through the lever 28. The block 110 is formed with an offset forked portion to surround the treadle rod 38 in one position of the block, and is movable out of engagement with the treadle rod by rotation of the block about the stud 112. The safety block 110 is held in the position to which it is adjusted by a spring 116 surrounding the stud 112 compressed between the block and a pair of lock nuts 118 on the end of the stud. To disengage the forked portion of the block from the treadle rod 38, the block is moved along the stud against the action of the spring until the forked portion of the block escapes the rod. The block may then be rotated to a position indicated in the dot-dash lines of Figure 3, where the block will no longer engage the arm 36 when the treadle is depressed. To facilitate moving the block, a suitable handle 120 is attached at one end to the block and extends toward the front of the machine. When the block is moved to a position with its forked portion out of engagement with the treadle rod, the treadle may be depressed to retract the lock bolt 74, and the positive stopping lever 94 will be disengaged 60 from the shoulder 104 through the connections, previously described, without actuating the high speed clutch.

The machine may, therefore, be rendered safe for manual rotation of the sewing shaft and adjustment of the sewing mechanism by shifting

the block 110 to its inoperative position and depressing the treadle 44. Also, the sewing machine can not be operated under power by accidental pressure on the treadle if the sewing shaft remains in its stopped position. Upon return of the block to the position indicated in Figure 2, the machine may immediately be operated in the usual way without causing the inconvenience or loss of time which would be necessary in disconnecting the machine from the rotating shaft 10 or in bringing the main driving shaft to rest before making adjustments or repairs. In order to insure that the high speed clutch will be released when the treadle rod rises, the connections between the arm 36 and the treadle rod 38 also comprise a clamp block 122 attached to the rod for engagement with the under side of the arm 36, as in the machine of the Topham patent.

The nature and scope of the several features of the invention having been indicated, and the preferred embodiment of the invention having been specifically described, what is claimed is:

1. A sewing machine having, in combination, stitch-forming devices, a sewing cam shaft for actuating the stitch-forming devices, a continuously rotating shaft for driving the sewing shaft, a high speed driving mechanism comprising a friction clutch for connecting the sewing shaft with the driving shaft, a low speed driving and stopping mechanism comprising a friction clutch arranged to retard and then drive the sewing shaft at low speed after the high speed driving clutch is actuated to disconnect the sewing shaft from the driving shaft, a treadle, connections between the treadle and the driving mechanisms to actuate the high speed clutch and to render the low speed driving and stopping clutch inoperative while the sewing shaft is being driven through the high speed mechanism, and a manually operable safety device for rendering the connections to the high speed driving mechanism inoperative while the treadle is moved to a position which renders the low speed mechanism inoperative.

2. A sewing machine having, in combination, stitch-forming devices, a sewing cam shaft for actuating the stitch-forming devices, a continuously rotating shaft for driving the sewing shaft, a high speed driving mechanism comprising a friction clutch for connecting the sewing shaft with the driving shaft, a low speed driving and stopping mechanism comprising a friction clutch arranged to retard and then to drive the sewing shaft at low speed after the high speed driving clutch is actuated to disconnect the sewing shaft from the driving shaft, a treadle, a rod connected to the treadle, connections from the rod to the low speed driving and stopping clutch inoperative, an arm for operating the high speed clutch, and a shiftable block mounted on the connecting rod for movement toward and away from a position in which the high speed mechanism will be operated by engagement of the block on the connecting rod with said arm when the low speed mechanism is rendered inoperative by movement of the treadle.

3. A sewing machine having, in combination, stitch-forming devices, a sewing cam shaft for actuating the stitch-forming devices, a stopping cam provided with a shoulder on the sewing cam shaft, a continuously rotating shaft for driving the sewing cam shaft, a high speed driving mechanism comprising a friction clutch for connecting the sewing shaft with the driving shaft, a low speed driving and stopping mechanism com-

prising a stopping lever cooperating with the stopping cam and a friction clutch arranged to retard and then drive the sewing shaft at low speed, said stopping lever thereafter being moved 5 against said cam to positively prevent further rotation of the sewing shaft, a treadle, connections between the treadle and the driving mechanisms to actuate the high speed clutch and to disengage the stopping lever from the cam and a manually operable safety device for rendering the 10 connections to the high speed driving mechanism inoperative while the treadle is moved to a position which causes the stopping lever to be disengaged from the stopping cam.

15 4. A sewing machine having, in combination, stitch-forming devices, a sewing cam shaft for actuating the stitch-forming devices, a continuously rotating shaft for driving the sewing shaft, a high speed driving mechanism comprising a 20 friction clutch for connecting the sewing shaft with the driving shaft, a low speed driving and

stopping mechanism comprising a friction clutch arranged to retard and then drive the sewing shaft at low speed after the high speed driving clutch is actuated to disconnect the sewing shaft from the driving shaft, a treadle, a rod connected to the treadle, connections from the rod to the low speed driving mechanism to render the low speed driving and stopping clutch inoperative, an arm for operating the high speed clutch, a shiftable block mounted on the connecting rod for movement toward and away from a position in which the high speed mechanism will be operated by engagement of the block on the connecting rod with said arm when the low speed mechanism is rendered inoperative by movement of the treadle, a handle carried by the block for manually changing the position of the block, and a spring for maintaining the block in the position to which it has been moved. 80 85 90 95
